UNITED STATES PATENT OFFICE.

HERMAN P. RUF, OF NEW YORK, N. Y.

LONG-THROW ATTACHMENT FOR FLAT-KNITTING MACHINES.

Application filed July 2, 1924. Serial No. 723,724.

To all whom it may concern:

Be it known that I, HERMAN P. RUF, a citizen of the United States, residing at New York city, borough of Manhattan, in **5** the county of New York and State of New York, have invented certain new and useful improvements in Long-Throw Attachments for Flat-Knitting Machines, of which the following is a specification.

- 10** This invention relates to flat knitting machine and more particularly to attachments for fringe or other machines of the general nature illustrated in the patent to Frel-loehr and Tisch, 457,265, August 4th, 1891. **15** Among the objects of this invention is to provide a long throw attachment for flat knitting machines which is operable at higher speeds and more positive in action than the usual lever mechanism at present **20** employed for the purpose.

Another object of this invention is to provide a long throw attachment operating without requiring the use of moving levers or the like, whereby more positive action is **25** obtained and with greater speed and less lost motion.

Another object of the invention is to provide a long throw attachment which shall be both light and strong, and shall occupy **30** no head room above the machine as in the case of the usual lever mechanism.

Still another object of this invention is to provide a long throw attachment having adjustable features to modify not only the **35** speed at which the attachment operates but also to permit of easy initial adjustment thereof when installing the attachment upon the machine.

With the foregoing and other objects in **40** view the invention consists in the arrangement and combination of parts hereinafter described and claimed, and while the invention is not restricted to the exact details of construction disclosed or suggested here-
45 in, still for the purpose of illustrating a practical embodiment thereof reference is had to the accompanying drawings, in which like reference characters designate the same parts in the several views, and in which—

50 Figure 1 is a front elevation of my invention.

Fig. 2 is a vertical transverse section on the line 2—2 of Fig. 1.

Fig. 3 is a sectional detail on the line 3—3 of Fig. 1 showing an end view of the **55** slide.

Fig. 4 is a detail view of the thread guide.

Referring now more specifically to the drawings, 10 represents a base frame for **60** a flat knitting machine carrying the various usual devices and attachments among which are conventionally represented a friction feed roll 11 for drawing the knitted material (see roller U of the above mentioned patent), a needle bar 12, and a rack or slide bar 13 adapted to slide in the frame at 14, said bar being fitted with a plurality of attached racks 15. Secured to the frame are standards or bars 16 bearing brackets or **65** supports 17 which are substantially parallel to the needle bar and are provided with longitudinal slots 17' at the free ends thereof. Adjustable bars or arms 18 are provided for the respective standards, and these arms are slotted longitudinally at one end at 18', bolts 19 being passed through the slots to attach the lower slotted ends of the arms to the base frames, the opposite ends being provided with bolts 20 engaging the **70** bars 17 at the slots 17', the arms or levers 18 being thus mounted for pivotal adjustment about the centers at 19. Journalled upon the arms and approximately midway **75** between the ends thereof are pinions 21 and wheels 22 each wheel having peripheral guide flanges 23 at the sides thereof. One pinion and one wheel constitute a coaxial pair, the effect being to give both wheels a like peripheral speed when the pinions are **80** actuated by the racks on the slide bar, the pinions meshing constantly with the respective racks aforesaid. A steel ribbon or wire approximately five or six diameters longer than the distance between the centers of **85** the wheels, the precise length, however, in each case to depend upon the relative diameters of the pinions and the wheels, is attached to the wheels at the ends by means of pins 25 or the like so as to wind up upon **90** the wheels between the flanges 23, the ribbon being stretched taut by adjusting the arms 18 so as to vary the distance between centers of the wheels.

A slide or runner 26 is mounted to slide **105** upon the bar 13, being actuated by the rib-

bon to which it is fastened by means of a clamp 27. The slide is equipped with two pairs of rollers 28 to ride upon the edges of the slide bar and two pairs of rollers 29 to ride upon the sides thereof thus insuring smooth and reliable operation of the attachment. The slide consists preferably of two portions, one of which 26^a has an integral arm 30 bearing the clamp 27 and a pair 10 of side rollers 29 for one side of the slide bar, while the other 26^b bears both pairs of edge rollers and a pair of side rollers. After being mounted upon the slide bar the two portions are fastened together as by 15 screws or the like. Mounted upon the slide is a thread guide 31 which consists of wire or any other suitable material and has an eye 32 through which the weft or other thread to be carried back and forth along 20 the needle bar is passed, while the other end is formed with a relatively long loop 33 through which a screw 34 is adapted to pass so as to secure said thread guide to the slide, said loop rendering the thread guide 25 slidable for vertical adjustment in relation to the needle bar.

The slide bar is actuated in any conventional or convenient manner as by push rods 35, corresponding to the pins K and K' of 30 Patent 457,265, supra, a series of which are rotatably mounted at each end of the slide bar, the movement of the bar being an intermittent to and fro motion, a push rod at the right causing the bar to move toward 35 the left and then rotating out of the way of the bar while another rod at the left rotates into alinement with the bar and then moves it toward the right. The movement of this bar being fairly rapid the racks cause a relatively high peripheral speed of the wheels 40 with the result that the ribbon winds and unwinds upon each wheel with considerable speed, thus causing the slide to travel the length of the needle bar within the merest fraction of a second. Should it be desirable 45 to regulate the throw of the slide a friction brake 36 can be used, which is pivotally secured to the bracket 17, a spiral spring 37 or the like being used to press the brake 50 against the wheel, the tension of the spring being adjustable by fastening an end thereof in any suitable manner to a collar 38 which is rotatable upon a rigid pin 39 so as to vary 55 the tension in the spring, the collar being secured against rotation by means of a thumb screw 40 or the like bearing against said pin.

The superiority of my attachment for the 60 purpose of throwing a weft thread along the needle bar of a flat knitting machine as for the making of fringes or the like and indeed for any other like purpose will be evident if it is remembered that my device is essentially rigid and positive in action, as well

as compact in construction, the centers of 65 the wheels being relatively close to the bar and consequently to the line of force whereby the rather considerable side spring with the resultant binding which occurs in a kinematic chain or other system of levers designed for a rapid straight line throw of 70 considerable length is eliminated. Since the ribbon is uniformly under tension a smooth and positive operation is insured, there being as a consequence no lost motion between 75 the racks and the pinions. Excellent results are obtainable with this device over a considerable range of speeds of the knitting machine including especially the higher 80 speeds.

I claim:

1. An attachment for knitting machines comprising a unitary rack and tube bar arranged for reciprocation along the machine, pinions co-operating with the bar, a plurality of spaced pulleys having fixed axes and rotatable in like direction by said pinions when the bar is reciprocated, a slide movable on said unitary rack and tube bar, and flexible means arranged to wind and 90 unwind on said pulleys in alternation to move the slide back and forth as the unitary rack and tube bar is reciprocated.

2. In a long throw attachment, the combination with a rack bar movable back and forth, of a plurality of spaced pinions rotatable in unison thereby around fixed axes, a plurality of wheels coaxial with the pinions and rotatable severally in like direction by said pinions, tension means longer than the distance between the centers of the aforesaid wheels attached to the peripheral portions of said wheels so as to wind and unwind intermittently thereupon as the same rotate in unison, and thread carrying means comprising a slide movable along the rack bar and adapted to grip the tension means so as to be moved back and forth thereby.

3. In a knitting machine provided with a reciprocating tube bar and a tube plate mounted slidably thereon, a flexible member for sliding said plate along said tube bar, a pair of pulleys mounted to rotate around fixed axes adjacent to the ends of said bar, a pinion mounted coaxially with each pulley, a rack member attached to each end of the bar and movable therewith and meshing with the adjacent pinion, whereby the pulleys are rotated simultaneously at each reciprocation of the bar, and means securing the ends of the flexible member upon the peripheries of the pulleys for winding thereon in alternation.

4. In an attachment of the character described, the combination of a plurality of spaced wheels rotatable around fixed axes, means to rotate the same in one direction,

and then in the opposite direction, taut tension means longer than the distance between the aforesaid wheels attached to the peripheral portions of said wheels so as to wind 5 and unwind intermittently thereupon, and thread carrying means comprising a slide adapted to grip said tension means for move-

ment thereby back and forth, one element of the rotating means aforesaid comprising a reciprocating bar upon which the thread **10** carrying means is supported.

In testimony whereof I affix my signature.

HERMAN P. RUF.
